ATTORNEY

WITNESS:

UNITED STATES PATENT OFFICE.

JAMES B. BAKER, OF SIOUX CITY, IOWA.

OIL BURNER.

Application filed October 15, 1925. Serial No. 62,674.

This invention relates to a burner for oil, the general object of the invention being to provide a device which can be used in stoves, furnaces and the like by being placed 5 on the grates thereof or which can be used separately and which can be manufactured to sell at low cost and which is so constructed that is not likely to get out of order.

Another object of the invention is to provide a pair of circular members which are spaced apart to receive a wick with means for introducing the fuel to a space formed at the center of the wick between the two 15 members, with means for directing the flames against the upper member, so that the same will be highly heated and thus the fuel will be vaporized as it passes into the space between the two members.

This invention also consists in certain other features of construction and in the combination and arrangement of the several parts, to be hereinafter fully described, illustrated in the accompanying drawings 25 and specifically pointed out in the appended claims.

In describing my invention in detail, reference will be had to the accompanying drawings wherein like characters denote 30 like or corresponding parts throughout the several views, and in which:

Figure 1 is a sectional view through a portion of a stove, showing the device in use.

Figure 2 is a longitudinal sectional view through the device.

Figure 3 is a plan view of the bowl.

Figure 4 is a bottom plan view of the lower member.

Figure 5 is a bottom plan view of the upper member.

Figure 6 is a perspective view of the wick member.

In these views, 1 indicates a conical support and 2 indicates a bowl-shaped member which is seated on the upper end of the support, this bowl-shaped member being formed with the outer flange 3 and the inner flange 4 which form an annular trough 5.

The flange 4 slopes inwardly and a spider 6 is connected to or formed with the upper end of said flange. A supply pipe 7 passes through the center of the spider and a concavo-convex disk 8 has a hole in its 55 center to receive the threaded end of said

pipe. This disk has the ribs 9 thereon, the lower enlarged portions of which rest upon the flange 4, so that the disk is supported by the flange, and said flange extends slightly into the concavity of the disk. A saucer-shaped wick 10 is placed over the member 8, said wick having a central hole 11 therein and a member 12 similar to member 8 is placed on the wick. The two members and the wick have vertical flanges 13 at their edges which extend slightly within the trough 5. The member 12 is provided with a staple-like handle 14. The opening 11 in the wick forms a recess between the members 8 and 12 to receive the oil passing from the pipe 7 and this oil will saturate the wick, which breaks it up into fine particles, and these particles are quickly vaporized when the members 8 and 12 become heated by igniting the oil collecting in the trough 5. The air will pass upwardly through the member 1 and, flowing into the trough over the flange 4, will direct the flames against the member 12 so as to highly heat it and thus vaporize the oil. After the burner is initially started from oil in the trough 5, it will, of course, be understood that it will continue to operate through the oil flowing into the same from tank 15 by means of pipe 7, the oil being vaporized as it reaches the members 8 and 12, and the vapors are ignited as they escape from between the members. The wick placed between the members 8 and 12 will divide the oil, so that it will be quickly vaporized and the vapor passing into the trough from between the members 8 and 12 will burn with a very hot blue-white flame. The burner will be free from carbonization.

I provide a drain pipe 16 which is connected with the trough, so as to take out any surplus oil that may gather in the trough. The staple 14 is used to lift the member 12 off of the device, so that the parts can be cleaned.

When the device is used in a stove or furnace, as shown in Figure 1, a packing 17 of earth or the like is placed around the member 1, so as to cause all the air to pass through said member.

It is thought from the foregoing description that the advantages and novel features of my invention will be readily apparent.

I desire it to be understood that I may make changes in the construction and in the

combination and arrangement of the several parts, provided that such changes fall within the scope of the appended claims.

What I claim is:—

- 5 1. A burner of the class described, comprising a bowl member having a central opening therein and an annular trough surrounding the opening, a pair of concavo-convex members seated upon the bowl, with the lower member extending over the opening and the edges of the members extending into the trough, a wick of the same shape as the members with an opening in its center which forms a space between the central parts of the members, a supply pipe connected with said space, means for causing air to pass through the opening in the bowl, a drain pipe connected with the annular trough in the bowl, a handle on the upper member for permitting the same to be removed from the lower member and the wick, and a conical member supporting the bowl and through which the air passes to the opening in the bowl.
- 20 2. In an oil burner, the combination with a bowl member provided with a central opening and an annular trough concentric with the opening, the wall of the opening having a radially extending spider, of an oil supply pipe threaded through the spider

centrally of the opening, an oil feed canopy with radial webs on the under surface of the interior of the canopy resting upon the inner wall of the trough, the canopy being operatively threaded on the upper extremity 35 of the oil supply pipe, said canopy comprising upper and lower concavo-convex plates, the under face of the upper plate having a depression concentric with the center of the supply pipe, a wick spread over substantially the entire surface of the convex face of the lower plate, excepting a central portion thereof, such portion corresponding with the diameter of the depression, whereby the oil may enter the depression and be 40 fed through capillary attraction through the medium of the wick to the entire marginal edge of the canopy, said marginal edge being downturned and extending substantially centrally into said trough, the 45 oil being fed acting to vaporize due to the generation of the heat in the trough and due to the air passing through the opening, a drain pipe connected with the trough to carry off the surplus oil, and means consisting of a shell for directing the air through the opening.

In testimony whereof I affix my signature.

JAMES R. BAKER
